APPARATUS FOR MAKING CHARCOAL STICKS

Irving Andrew Hultberg, Irvington, N. J., assignor to American Art-Char, Inc., a corporation of New Jersey

Application July 30, 1932. Serial No. 627,020

9 Claims. (Cl. 202—97)

This invention relates to an improved apparatus for converting wood into charcoal and more particularly to an apparatus for forming charcoal pencils used by artists when making charcoal sketches. While it has been stated that the device is used for making charcoal pencils, it will be obvious that charcoal in stick formation and used for purposes other than drawing may be formed in the improved apparatus and that the sticks may be of any length and diameter desired.

When sticks or rods of wood are converted into charcoal, they have a tendency to warp and become distorted so that they cannot be conveniently held in a person's hand when used as a pencil and therefore one object of this invention is to provide an apparatus of such construction that pressure may be applied to sticks of wood while they are being converted into charcoal and thereby prevent them from warping and also cause the charcoal pencils when formed to be of substantially an even diameter.

Another object of the invention is to permit the sticks of wood to be packed in an oven forming part of the apparatus in tiers, one above another, and not only retain the sticks out of engagement with each other but also permit hot air and gases driven off from the wood to circulate freely in the oven and cause the sticks to be quickly converted into charcoal.

Still another object of the invention is to provide a device of this character which is simple in construction, easy to operate, and not liable to get out of order when in use.

With these and numerous other objects in view, my invention consists in the novel features of construction, combination and arrangement of parts as will be hereinafter referred to and more particularly pointed out in the specification and claims.

In the accompanying drawings forming a part of this application:

Figure 1 is a perspective view of the improved charcoal forming apparatus with portions of the outer hood broken away;

Figure 2 is a vertical section taken transversely through the apparatus;

Figure 3 is a perspective view of the outer hood with the front broken away and shown in section;

Figure 4 is a perspective view of the oven enclosed by the hood;

Figure 5 is a fragmentary perspective view of a wood supporting tray forming part of the apparatus.

Figure 6 is a perspective view showing a num-

ber of the trays arranged in tiers and a pressure applying weight in place.

In describing the invention, I shall refer to the drawings in which similar reference characters designate corresponding parts throughout the several views and in which 1 designates the oven. This improved apparatus is employed to form sticks of charcoal which may be used as pencils or for other purposes if they are of the proper length and diameter. The apparatus comprises briefly an oven 1 in which trays 2 and spacers 3 are stacked as shown in Figure 2, a weight 4 for applying pressure to prevent warping of sticks of wood 5 while being converted into charcoal and a hood 6 which is open at its bottom in order that it may be easily set in place about the oven or removed from the same.

The oven 1 is rectangular in shape as shown in Figure 4 and may be of any dimensions desired. It is open at its front for access to its interior and in order to close the oven after it has been charged, there has been provided a door 7 hinged as shown at 8 and carrying a suitable number of fasteners 9 serving not only to secure the door when closed but also as handles by means of which the door may be opened and closed. Upper and lower strips 10 and 11 which extend longitudinally of the oven project transversely from its side walls and are formed with notches 12 and 13 to receive guide rods 14 carried by the hood 6 and not only guide movement of the hood into and out of place but also retain walls of the hood and oven in spaced relation to each other and permit air to circulate freely about the oven when the hood is in place. Handles 15 are provided at opposite sides of the hood in order that it may be easily lifted.

When the oven is charged, the sticks of wood are set in place upon the trays 2 and since the trays are formed of corrugated sheet metal each tray is formed with longitudinally extending pockets to receive the sticks. As the trays are placed within the oven one above another, a spacing sheet 3 is set in place upon each tray and the weight 4 rests upon the sheet on the uppermost tray of the stack. Openings 16, 17 and 18 are formed centrally of the trays, spacing sheets and weight and therefore, hot air and gases may pass upwardly through the stack while the sticks of wood are being converted into charcoal. It should also be noted that side walls of the oven carry front and rear rods 19 corresponding to the rods 14 and serving to engage sides of the stack and retain the same in spaced relation to walls of the oven in order that a good

circulation may take place. The air and gases accumulate in the upper portion of the oven and pass out through the valve 20 and after leaving this valve pass out through an opening 21 formed 5 in the top of the hood. This opening is controlled by a closure plate 22 slidably mounted by cleats 23 in order that it may be slid into and out of covering relation to the opening and thereby control the temperature of the space within the 10 hood about the oven.

When the improved charcoal forming apparatus is in use, the trays are loaded with sticks of wood of the desired length and thickness and the loaded trays are placed in the oven 1 in 15 stacked formation with a spacing sheet upon each tray and the weight resting upon the upper spacing sheet. The door 7 is closed and secured and the hood set in place about the oven. Heat is supplied to the oven by setting it upon a stove or in any other manner desired and since the 20 hood is formed as a hollow shell filled with insulation as shown at 24, heat will be confined about the oven and the oven retained at such a temperature that the sticks of wood will be quickly 25 converted into charcoal. By properly adjusting the valve 20 and plate 22, passage of hot air and gases from the oven and hood can be controlled and the oven retained at the desired temperature. Since the weight 4 exerts pressure upon the stack 30 of trays and spacing plates, the sticks of wood will be retained in a flattened condition and prevented from warping as they are converted into charcoal and the resulting charcoal will be in the form of straight sticks which can be easily 35 held in a person's hand and used as a pencil when making charcoal sketches. The pockets of the trays are V-shaped in cross section and therefore, sticks may be held firmly in place therein even if they are not of a predetermined diameter and also sticks placed in the pockets of 40 one tray may be of a different diameter from sticks carried by another tray. Pressure exerted upon the stack of trays and spacing sheets can be controlled by providing a series of blocks 45 of different weight or a single block can be used and have flexible wires extending from it over guide pulleys and carrying counterweights.

From the foregoing description of the construction of my improved device, the operation thereof 50 and the method of applying the same to use will be readily understood. It will be seen that I have provided a simple, inexpensive and efficient means for carrying out the objects of the invention and while I have particularly described the elements best adapted to perform the functions 55 set forth, it is obvious that various changes in form, proportion and in the minor details of construction may be resorted to without departing from the spirit or sacrificing any of the principles 60 of the invention.

Having thus described the invention what is claimed is:

1. Apparatus for making charcoal pencils comprising an oven having a closure movable into and out of a closed position whereby access may be had to the interior of the oven, a stack of stick holding trays and spacing sheets between the trays in said oven, the oven being provided with an upwardly extending outlet pipe for hot air 70 and gases at its top, and a hood disposed about said oven in spaced relation thereto and provided with an opening at its top through which said pipe projects.

2. Apparatus for making charcoal pencils comprising an oven open at one side thereof and

having a door movable into and out of closing relation thereto, a stack of trays insertable into said oven when its door is open, each tray being disposed horizontally and bent to form a plurality of elongated stick receiving pockets, spacing sheets between said trays serving as covers for said pockets, and a weight resting upon the stack of trays and sheets.

3. Apparatus for making charcoal pencils comprising an oven open at one side thereof and having a door movable into and out of closing relation thereto, a stack of trays insertable into said oven when the door is open, each tray being disposed horizontally and consisting of a sheet crimped to form a plurality of elongated stick receiving pockets, spacing sheets disposed between said trays and serving as covers for said pockets, a weight resting upon the stack of trays and sheets, the trays, sheets and weight being formed with openings to permit passage of air and gases upwardly through the stack, and means being provided within the oven to retain the stack spaced from walls of the oven and permit circulation of air in the oven about the stack, said oven having a valve controlled outlet at its top.

4. Apparatus for making charcoal pencils comprising an oven open at one side thereof and having a door movable into and out of closing relation thereto, a stack of trays insertable into said oven when the door is open, each tray being 105 formed with a plurality of stick receiving pockets, spacing sheets between the trays serving as covers for the pockets, a weight resting upon the stack of trays and sheets and rods carried by walls of said oven and extending vertically with 110 in the oven in spaced relation to the walls for engaging sides of the stack to retain the stack spaced from walls of the oven, an outlet for air and gases being provided at the top of said oven.

5. Apparatus for making charcoal pencils 115 comprising an oven open at one side thereof and having a door movable into and out of closing relation thereto, a stack of trays insertable into said oven when the door is open, each tray consisting of a metal sheet crimped to form elongated stick receiving pockets parallel to each other and each V-shaped in cross-section, spacing sheets between said trays serving as covers for the pockets, a weight resting upon the stack of trays and sheets, the trays, sheets and weight 120 being formed with openings to permit passage of air and gases upwardly through the stack, an outlet for air and gases being provided at the top of the oven, and spacers carried by walls of said oven and extending vertically within the oven in 125 spaced relation to the walls for engaging the stack to retain the stack spaced from walls of the oven.

6. Apparatus for making charcoal pencils comprising an oven open at one side thereof and 135 having a door movable into and out of closing relation thereto, a stack of trays insertable into said oven when the door is open, each tray being bent to form a plurality of elongated stick receiving pockets, spacing sheets between the trays 140 serving as covers for the pockets, a weight resting upon the stack of trays and sheets, rods carried by walls of said oven and extending vertically within the oven in spaced relation to the walls for engaging opposite sides of the stack to retain 145 the stack spaced from walls of the oven, and an outlet pipe for air and gases at the top of said oven.

7. Apparatus for making charcoal pencils comprising an oven open at one side thereof and

having a door movable into and out of closing relation thereto, a stack of trays insertable into said oven when the door is open, each tray consisting of a sheet crimped to form elongated stick 5 receiving pockets, spacing sheets disposed between said trays and serving as covers for the pockets, a weight resting upon the stack of trays and sheets, the trays, sheets and weight being formed with openings to permit passage of air 10 and gases upwardly through the stack, rods carried by walls of said oven and extending vertically within the oven in spaced relation to the walls for engaging opposite sides of the stack to retain the stack spaced from walls of the oven, 15 and an outlet pipe for air and gases at the top of said oven.

8. Apparatus for making charcoal pencils comprising an oven, means for supporting sticks of wood in the oven for conversion into charcoal, 20 a hood open at its bottom and set in place about the oven, said oven having outwardly projecting ribs at its sides formed with notches, and rods in said hood carried by its walls and extending

vertically in spaced relation thereto and engaged in the notches of said ribs to hold walls of the hood and oven in spaced relation to each other and prevent shifting of the hood horizontally relative to the oven.

9. Apparatus for making charcoal pencils comprising an oven, means for supporting sticks of wood in the oven for conversion into charcoal, a hood open at its bottom and set in place about the oven, said oven having outwardly projecting ribs at its sides, rods in said hood carried by its walls and extending vertically in spaced relation thereto and engaging said ribs to hold walls of the hood and oven in spaced relation to each other, an opening being formed in the top of the hood, the oven being provided with an outlet pipe extending upwardly therefrom and projecting through the opening in the hood, and a control plate for the opening slidably mounted for movement into and out of closing relation to the opening about the outlet pipe.
